Primary Examiner — Mitchell I. Siegel

(57) **CLAIM**

The ornamental design for a console for providing virtual reality environments, as shown and described.

DESCRIPTION

FIG. 1 is a perspective view of a console for providing virtual reality environments showing my new design;

FIG. 2 is a perspective view of a console for providing virtual reality environments showing my new design;

FIG. 3 is a right side view thereof;

FIG. 4 is a top view thereof;

FIG. 5 is a left side view thereof;

FIG. 6 is a bottom view thereof;

FIG. 7 is a front view thereof; and,

FIG. 8 is a rear view thereof.
